A. J. PAULSON.

CONTROLLING VALVE FOR MULTIPLE FUEL SUPPLY PIPES.

APPLICATION FILED MAR. 26, 1918.

1,327,252.

Patented Jan. 6, 1920.

UNITED STATES PATENT OFFICE.

ANDREW J. PAULSON, OF SALT LAKE CITY, UTAH.

CONTROLLING-VALVE FOR MULTIPLE FUEL-SUPPLY PIPES.

1,327,252.

Specification of Letters Patent.

Patented Jan. 6, 1920.

Application filed March 26, 1918. Serial No. 224,910.

To all whom it may concern:

Be it known that I, ANDREW J. PAULSON, a citizen of the United States, residing at Salt Lake City, in the county of Salt Lake 5 and State of Utah, have invented certain new and useful Improvements in Controlling-Valves for Multiple Fuel-Supply Pipes, of which the following is a specification.

10 My invention relates to internal combustion engines, and has for its object to provide a valve for controlling the flow of liquid fuel from multiple fuel supplies, whereby a highly volatile oil may be used in 15 starting and warming up the engine and another less volatile and more economical fuel introduced and jointly used with the highly volatile or the supply of the highly volatile oil shut off and the less volatile oil introduced after the engine is partially warmed 20 and started.

A further object of the present invention is to provide a valve whereby the highly volatile fluid may be directed to the combustion 25 cylinders without passing through the carburetor for an initial charge to start the engine during cold weather, and at times when the carburetor is filled with low volatilizing fluid.

30 A further object is to provide a valve whereby water may be directed into and for use in the engine when the less volatile fuel is used, and which valve will be closed and drain itself when it is turned to allow highly 35 volatile fuel to flow through the carburetor of the engine.

These and other objects which are apparent I accomplish with the device illustrated in the accompanying drawings in which 40 similar letters and numerals of reference indicate like parts throughout the several figures and are described in the specification forming a part of this application and pointed out in the appended claims.

45 In the drawings in which I have shown a substantial embodiment of my invention Figure 1 is an elevation of the front portion of an automobile with parts omitted to show my valve thereon. Fig. 2 is an elevation of 50 the device. Fig. 3 is a vertical section on line 3 3 of Fig. 5. Fig. 4 is an elevation showing a different view from that shown in Fig. 2. Fig. 5 is a plan view of the device with the valve turned to allow the 55 less volatile fluid to flow. Fig. 6 is a transverse section on line 6 6 of Fig. 2. Fig. 7

is a section on line 7 7 of Fig. 4. Fig. 8 is a plan of the indicating dial used in operating the device. In the use of an internal combustion engine, it is desirable to economize 60 in the cost of fuel by starting and warming up the engine on high grade fuel, and then by introducing and using a cheaper fuel for the general use of the engine.

In the use of internal combustion engines 65 I have found that increased power may be developed by using a small quantity of water with the less volatile fuel such as distillate. Also that burned or partially burned carbon will accumulate in the cylinders of the engine and prevent full development of the power of the engine, and that when small quantities of water are used with the fuel in the engine it will be freed 70 from such deposit of carbon. The present 75 invention is to provide a valve and other coacting elements which may be easily and quickly attached to most engines now in use whereby the engine may be supplied with different or commingled qualities of liquid 80 fuel as desired, and also to supply water or steam into the engine when the less volatile fuel is used, with a drain from the device to prevent injury from freezing, which drain is 85 closed when the less volatile fuel is used and opened when the highly volatile fuel is used.

In the drawings the valve casing is shown at A having a central bore 1. Pipe receiving lugs 2, 3, 4, 5, 6 and 7 are integrally formed on and radially extend from said casing, and each is centrally bored and externally threaded. The said bores are extended radially inward and open into the said central bore 1. Four of said bored lugs are on one transverse plane and the other two are on another plane. A drain vent 18 is also bored on the last described plane through the wall of said casing and which opens into said central bore 1. The inner wall of said casing A has two recesses 8 and 9 cut or formed therein which open into said central bore 1. The recess 8 connects with the bore in the lug 2 and the recess 9 connects with the bore in the lug 5. The valve stem 11 has a transverse diametrically disposed bore 12 on the plane of the bored lugs 2, 3, 4 and 5, and two similar bores 13 and 14 respectively on the plane with the bored lugs 6 and 7. The said casing A has shoulders *a* and *b* formed on its upper end 100 and a pin 15 is radially secured in said valve stem 11 to engage with said shoulders and 105 110

limit the rotation of said valve stem. The said valve stem 11 may be rotated by means of a rod 17, as limited by said pin 15 and the said bores 12, 13 and 14 brought into alignment with the different radial bores in said casing A. A pipe 28 is screwed on the said lug 2 and connects a highly volatile fuel tank B with said casing A. The pipe 16 is secured on the said lug 3 and connects 10 the less volatile fuel tank, not shown, with the casing. The water pipe 19 is screwed on lug 6 and connects the water supply with the casing A and the pipe 20 which is screwed on the lug 7 leads to the engine 15 through the carbureter. A primer pipe 21 connects the said lug 4 with the intake manifold of the engine, whereby highly volatile fuel may be introduced into the engine for starting without it having to pass through 20 the carbureter. The lug 5 is connected with the carbureter C and by partially rotating the said valve stem 11 fuel from either tank or from both may be directed to the engine through the carbureter. It will be seen that 25 with the valve stem as shown in Fig. 6 and pin 15 against shoulder *a* the less volatile fuel will flow and the highly volatile fuel will be cut off, also the bore 13 will be in alignment with the bored lugs 6 and 7 and 30 the desired amount of water will pass the valve and be introduced into the engine. By partially rotating said valve stem clockwise by means of the rod 17 and as indicated by the dial 22 to the position marked "Gas" 35 thereon the bore 12 will be brought into alignment with the bored lug 2 and the highly volatile fuel will flow therethrough and through the recess 9 and bored lug 5 to the engine, and if the rotation is continued 40 to the position marked "PR" of said dial the bore 12 will be in alignment with the bored lug 4 and the highly volatile fuel will flow through the bored lug 2, recess 8, bore 12 and bored lug 4 to the intake manifold of the engine for priming the engine. 45 When the said stem is rotated to the position marked "Off" on the dial 22 and the pin 15 against the shoulder *b* the flow of fuel will be cut off. When water is flowing through 50 the bores in the lugs 6 and 7, and the bore 13 it will enter the engine through the intake manifold D where it will commingle with the less volatile fuel and aid in keeping the cylinders free from carbon as well as producing 55 a mixture more desirable and with greater strength and aid in keeping the temperature of the engine lower; and with

the valve stem 11 turned so that bore 14 is in alignment with the bores in lugs 6 and 7 the bore 13 will be in alignment with the 60 drain bore 18 and all water will be drained from the device through said bore 18. The essential features of my device consist in having the fluid pass through and be controlled by one economical valve whereby the 65 engine may be started by the use of highly volatile fuel and by simply turning the valve stem; a less volatile fuel may be used in the engine with water or steam if desired and which water will not freeze in the device 70 during extremely cold weather.

Having thus described my invention I desire to secure by Letters Patent and claim:—

1. In a valve of the class described the combination of a casing having a tapered axial bore, and having recesses in its inner wall which open into said bore; centrally bored lugs integral with said casing and extending radially therefrom, and with the bore of each opening into the axial bore of 80 said casing two of which bores open into said recesses; a transversely bored valve operable in said casing the bores of which may be brought into alignment with the bores in 85 said lugs in pairs to conduct liquid fuel from a highly volatile fuel tank to the cylinders of an engine or to the carbureter as desired, also from a less volatile fuel tank to the same carbureter and from a water supply to the carbureter as desired; and 90 means to rotate said valve to open and close said bores.

2. In a valve of the class described the combination of a casing having a central axial bore and two recesses in its inner wall 95 which open into said central bore; axially bored radially disposed integral lugs on said casing the bores of which open into said central bore two of which bores open into said recesses; other lugs on a different plane bored to connect with said central bore; a drain conduit from said central bore through the wall of said casing; a transversely bored valve operable in said casing the bores of which may be brought into 100 alignment with the bores in said lugs, with one of said bores opening into one or the other of said recesses adjacent a lug when in alignment with the bore in the diametrically opposite lug.

In testimony whereof I have affixed my signature.

ANDREW J. PAULSON.
